Martin Joachimson

UNITED STATES PATENT OFFICE.

MAX A. SKALL, OF NEW YORK, N. Y.

DESIGN FOR A DISPLAY-CASE WITH MIRROR.

• 50,268.

Specification for Design.

Patented Feb. 6, 1917.

Application filed October 4, 1916. Serial No. 123,780. Term of patent 7 years.

To all whom it may concern:

Be it known that I, MAX A. SKALL, a citizen of the United States, and residing at New York city, in the county and State of New York, have invented a new, original, and ornamental Design for a Display-Case with Mirror, of which the following is a specification, reference being had to the accompanying drawing, forming part thereof.

The drawing is a perspective of a display case, embodying the new design.

I claim:

The ornamental design for a display case with mirror as shown.

MAX A SKALL.
